SPRING-PRESSURE REGULATOR FOR PUMPS.

No. 888,803.

Specification of Letters Patent.

Patented May 26, 1908.

Application filed March 15, 1907. Serial No. 362,459.

To all whom it may concern:

Be it known that we, LOUIS W. HASKELL, WALTER C. PETTY, and EUGENE L. TESSIER, citizens of the United States of America, and 5 residents, respectively, of New York city, county and State of New York; Savannah, county of Chatham, State of Georgia, and Charleston, county of Charleston, State of South Carolina, have invented certain new 10 and useful Improvements in Spring-Pressure Regulators for Pumps, of which the following is a specification.

This invention relates to regulators for pumps and particularly pumps for pumping 15 liquids such as oil.

One object of the invention is to provide a regulator of simple and durable construction which may be readily applied to pumps of different types and by means of which the 20 supply of liquid furnished by such pumps, acting under varying pressures, is efficiently controlled.

A further object of the invention is to furnish a pump-regulator which acts as a reser- 25 voir to receive more or less of the liquid according to the pressure existing in the pump-cylinder and to force the liquid back upon the piston during the return-stroke, whereby the liquid is prevented from being discharged 30 from the pump through the discharge-pipe, or through a relief-valve, as has been customary.

A further object is to automatically de- 35 velop a gradually increasing hydraulic pressure (as in the cylinder of a hydraulic press) by gradually decreasing the quantity of liquid delivered to the press cylinder while the pressure of such liquid is simultaneously increased.

40 With these ends in view the invention consists in the novel features and combinations of parts to be hereinafter described and claimed.

The accompanying drawing shows in ele- 45 vation and partly in section a two-cylinder press-pump having two of my improved regulating devices applied thereto, one to each cylinder.

In the drawing reference numeral 1 indi-

cates the pump cylinders and 2 the pistons 50 which reciprocate in said cylinders through stuffing-boxes 3.

4 is the check-valve of the usual construc- 55 tion by means of which the liquid is forced under pressure from one cylinder to the dis- charge-pipe 5, common to both cylinders.

The improved regulator comprises a regu- 60 lator-cylinder 6 which extends at right angles to the pump-cylinder 1 and communi- cates therewith by means of a short-pipe 7 threaded into both cylinders. The capacity of the regulator cylinder is made equal to that of the pump-cylinder in order that the former cylinder may, if required, receive all 65 the liquid from the latter. Within the regu- 70 lator-cylinder 6 there is a piston 8 movable in upward and downward direction through a stuffing-box 9 at the upper end of said cylin- 75 der. The cylinder 6 is formed at its upper end with laterally extending perforated lugs 80 9* in which are secured parallel upright rods 10. Said rods are threaded at their upper ends and they are connected by a cross-piece 11 movable freely in vertical direction on 85 said rods and adjustable thereon by means of nuts 12. The regular piston 8 is threaded at its upper end into a crosshead 15 guided on the rods 10. Secured to and extending up- 90 wardly from said crosshead 15 is a spindle 13 passing freely through an opening in the 80 cross-piece 11 so as to be guided in the latter. A helical spring 14 embraces the spindle 13 between the cross-piece 11 and the crosshead 15 and normally holds the piston in its lower- 95 most position in which it completely fills the regulator-cylinder. The compression of the spring may obviously be adjusted by means of the nuts 12 whereby the cross-piece 11 may be forced downwardly on the rods 10 in order to compress the spring to the required extent.

For the purpose of preventing the "ham- 95 mering" of the piston 8 and to ease down its movement the spindle 13 is extended up- 95 wardly beyond the cross-piece 11 to a sub- stantial extent and provided at its upper end with a collar 16 which is engaged by a rel- atively small helical spring 17 embracing the

spindle and interposed between said collar and said cross-piece. The tension of the spring 17 may be regulated by means of nuts 18 threaded on the spindle above the collar 16 and by means of which the latter is held on said spindle. For the same purpose above indicated the piston 8 is cushioned by a dash-pot. This dash-pot is preferably formed by making the nut or gland 19 of the stuffing box 10 9 of cup-shape so as to form a dash-pot cylinder and providing the piston 8 with a dash-pot piston 20 designed to fit within said nut or gland. This piston 20 is preferably cylindrical in form, as shown, and threaded on 15 the upper end of the regulator-piston, so as to be vertically adjustable thereon. By this arrangement the position of the dash-pot piston may be readily made to correspond with that of the stuffing-box nut. In some 20 cases the cushioning spring 17 or the dash-pot may be omitted, but it is always preferable to employ at least one of these cushioning devices.

The operation of the regulator is as follows:

25 Supposing the pump to be operating at a low pressure, the oil or other liquid is sucked from the source of supply into the pump cylinder 1 upon the outstroke of the piston. During the instroke or compression stroke of 30 the piston, the oil is discharged through the check-valve 4 and thence into the discharge-pipe 5. Under these conditions the pressure within the pump-cylinder is not sufficient to affect the regulator-spring 14 which retains 35 the regulator-piston in its normal or closed position, and all the oil is discharged. However, upon a predetermined increase of the pressure the action of the regulator-spring will be overcome and the regulator-piston 40 will be forced upwardly to a greater or less extent, depending on the pressure, thus allowing the corresponding amount of the oil to ascend, under the action of the pump-piston, into the regulator-cylinder, instead 45 of being discharged through the valve 4 into the discharge-pipe. Upon the return-stroke of the pump-piston the spring will return to its normal position and the oil will be permitted to flow back into the pump-cylinder, 50 as will be understood. Accordingly the next charge of oil which is sucked into said cylinder will be diminished in quantity by an amount corresponding to that which entered and flowed back from the regulator-cylinder, 55 or, in other words, will be equal to the amount which was forced out into the discharge-pipe. When the pressure is still further increased the spring will be compressed to such an extent that the regulator-cylinder 60 will be entirely filled with oil and will take up all the oil from the pump-cylinder, the capacity of said cylinders being the same, as

before explained. Thus no oil whatever will escape to the discharge-pipe. On the return-stroke of the piston this oil will flow back 65 into the pump cylinder as before and in so moving back and forth the power of the pump is taken up by the compression of the spring instead of delivering oil. When the pressure is reduced there is a corresponding 70 reduction of the amount of oil taken into the regulator-cylinder; and hence the oil will again begin to be forced out through the discharge-pipe. Thus the regulator reduces the flow of oil upon predetermined increases 75 in pressure and proportionally to such increases, and when a certain high pressure is reached, cuts off the supply entirely. The regulator is adjusted to these pressures by means of the nuts 12, as already pointed out. 80

It is obvious that the pumping-piston and regulator-piston do not necessarily have the same amplitude of movement. When the pumping-piston has a very long stroke and it is desired to use a spring having a short movement this can be done by increasing the area 85 of the regulator-cylinder and piston and proportionately decreasing their length, as will be understood.

The improved regulator may be applied, 90 if desired, to the discharge-pipe instead of to the pump-cylinder. In this case the discharge check-valve in the pump must be removed and a check-valve placed in the discharge-pipe at a point beyond the regulating 95 device—that is to say, between the regulating device and the press or other mechanism to which the oil is to be supplied. This change of the check-valve is made necessary by the fact that the pump-cylinder and regulating device must deliver oil to each other 100 in both directions.

The improved regulator may be very readily applied to any pump and is very simple in construction and effective in operation. 105 Further, the device may be readily adjusted, this adjustment being possible while the pump is in operation.

Having thus described my invention, I claim:

1. The combination with a pump cylinder and a pump piston therein, of a regulator cylinder, a reciprocating piston therein, a stuffing-box through which said piston passes into said cylinder and which embodies a gland forming a dash-pot cylinder, a dash-pot piston carried by said regulator piston, and a spring acting on said regulator piston to normally hold the same in position. 115

2. The combination with a pump cylinder and a pump piston therein, of a regulator cylinder, a reciprocating piston in said regulator cylinder, a stuffing-box through which said piston passes into said cylinder and 120

which embodies a nut or gland forming a dash-pot cylinder; a dash-pot piston carried by said regulator piston and arranged to fit within the cup-shaped nut when the regulator piston is at the limit of its inward movement.

3. A regulator for pumps, comprising a regulator-cylinder adapted for attachment to the pump-cylinder, a reciprocating piston 10 in said regulator-cylinder, a stuffing-box through which said piston passes into said cylinder and which embodies a cup-shaped nut or gland forming a dash-pot cylinder, a dash-pot-piston carried by said regulator 15 piston and arranged to fit within said cup-shaped nut when the regulator-piston is at the limit of its inward movement, and a spring acting on said regulator-piston to

normally hold the same in the aforesaid position. 20
